UNITED STATES PATENT OFFICE.

SWITS CONDÉ, OF OSWEGO, NEW YORK.

DESIGN FOR A KNIT SHIRT.

SPECIFICATION forming part of Design No. 14,996, dated May 13, 1884.

Application filed December 11, 1883. Term of patent 7 years.

To all whom it may concern:

Be it known that I, SWITS CONDÉ, of Oswego, in the county of Oswego, in the State of New York, have invented a new and original Design for Knit Shirts, of which the following, taken in connection with the accompanying drawing, is a full, clear, and exact description.

The nature of my design is fully represented in the accompanying illustration, to which reference is had.

A represents the body of a knit shirt; B, the front thereof, provided with the usual loops and knotted cords. C and D and E E are ornamental vertical rows of stitches across the heels of the loops and cords.

What I claim is—

The design for knit shirts herein shown, consisting of the ornamental vertical rows of stitches E E across the heels of the loops and cords.

In testimony whereof I have hereunto signed my name and affixed my seal, in the presence of two attesting witnesses, at Oswego, in the county of Oswego, in the State of New York.

SWITS CONDÉ. [L. S.]
